UNITED STATES PATENT OFFICE.

ALBERT WIEGEL, OF CASSEL, GERMANY.

NECKTIE-HOLDER.

1,022,807.

Specification of Letters Patent. Patented Apr. 9, 1912.

Application filed August 16, 1911. Serial No. 644,465.

To all whom it may concern:

Be it known that I, ALBERT WIEGEL, a subject of the German Emperor, and residing at Cassel, Germany, have invented certain new and useful Improvements in Necktie-Holders, of which the following is a specification.

The present invention has reference to a new construction of necktie holder, and relates more specifically to a one-part holder 10 to be permanently attached to the tie, in the form of a V-shaped housing, into which the head of the collar button is introduced and in which it is retained without danger of becoming unintentionally unfastened.

15 In order to make my invention more readily understood, I will now describe it with reference to the accompanying drawings, in which—

Figure 1 represents a perspective front 20 view of the new device; Fig. 2 is a rear view, and Fig. 3 a side view thereof; Fig. 4 shows a vertical section through the holder with the adjacent necktie part.

The holder, of any suitable material, preferably stamped sheet metal, consists of the front part *a*, the middle part *b* with cut-outs *c*, and the rear part *d* with apertures *e* for fastening purposes. The front and rear parts extend approximately rectangularly to 25 the connecting middle part *b*. At the upper edges of the members *a* are provided stop plates *f*. The cut-outs *c* are provided at the top with rearwardly extending enlargements *c'*, into which the head of the collar button *h* 30 is introduced in slanting direction, as shown in dotted lines in Fig. 4 as at I. It is then slid into the straight portion of the cut-outs, when the stop plates *f*, taking over the button head, will effectively prevent the parts 35 from becoming accidentally disconnected again. The position II in Fig. 3 shows the proper position of the button relative to the holder when in use.

For detaching the tie, it is tilted a little and then drawn downwardly, whereby the 45 button head comes clear of the stop plates *f* and slides into the enlarged cut-out portions *c'* and then out of the housing. On account of the V shape of the housing, the cut out portions *c'* are far enough apart to permit 50 the easy insertion or removal of the head of the collar button, without disturbing the walls of the housing.

The more or less resilient necktie part *g* is 55 made use of to prevent the button from extending too far into the housing, and serves to retain it in its operative position below the little stop plates.

The manner of securing the described holder to the tie is immaterial; as shown, 60 holes *e* are provided for sewing it on, but it may also be attached in any other suitable manner, for instance by rivets, wire staples or the like.

What I claim is:—

A necktie holder consisting of an integral 65 piece of sheet metal stamped and pressed to form a V-shaped housing, comprising a front part with a central, upwardly opening slot and with stop-plates at the upper edges, 70 fastening members, and side parts angularly interposed between said front part and said fastening members, said side parts having longitudinal slots terminating in rearwardly 75 extending enlargements at the top, to permit the insertion or removal of a collar button beneath said stop plates, substantially as and for the purpose set forth.

In testimony whereof I affix my signature in presence of two witnesses.

ALBERT WIEGEL.
